UNITED STATES PATENT OFFICE.

LEONARD A. YOUNG, OF HIGHLAND PARK, MICHIGAN.

FLOOR-BOARD FOR AUTOMOBILES.

1,343,168.

Specification of Letters Patent.

Patented June 8, 1920.

Application filed February 10, 1919. Serial No. 276,228.

To all whom it may concern:

Be it known that I, LEONARD A. YOUNG, of Highland Park, county of Wayne, State of Michigan, have invented certain new and 5 useful Improvements in Floor-Boards for Automobiles, of which the following is a specification.

This invention relates to floor boards for automobiles and to an arrangement and construction thereof whereby strength is combined with lightness, rapping and checking are obviated and the desired conformation is obtained without exposing any unfinished marginal portions.

10 The invention consists in the matters hereinafter set forth, and more particularly pointed out in the appended claims.

In the drawings:

Figure 1 is a plan view of the underside 20 of a floor board that embodies features of the invention;

Fig. 2 is a view in longitudinal section therethrough;

Fig. 3 is a view in detail showing application of a marginal binding strip;

Fig. 4 is a similar view, showing modification of the body of the floor board;

Fig. 5 is a view in section and in detail showing a batten strip fully expanded;

30 Fig. 6 is a view in detail showing the method of application of the batten strip; and

Fig. 7 is a view in detail of a modified batten strip.

35 As herein shown in preferred form, a floor board of the desired dimensions and contour is formed of a series of pieces 1 that are each provided with transverse dovetail slots 2, having the usual bevel or under-cut sides.

40 A laterally expandable batten strip is provided for each dovetail groove, and is preferably formed with a transversely-crowned web 3 and marginal flanges or beads 4 that are arranged to receive and close over the sharp angled margins of the pieces 1 along the grooves 2. Each batten strip is dimensioned for ready insertion in one of the grooves 2 before expansion and is likewise arranged so that when flattened into the groove as indicated in Fig. 6, it firmly engages under the dovetailed edges while the marginal flanges 4 are rolled down flat and

act as shields over the dovetailed edges, thoroughly protecting and shielding them 55 from splintering or checking off.

A sheet metal strip 5 is secured along each margin of the assembled floor board, the strip having inturned flanges 6 that grip the floor board between them. This strip 60 may be bent to follow any curve to the floor board, if it has rounded or irregular contour.

A floor covering 7 of linoleum or like sheet material may be incorporated in the structure in which instance, as indicated in Fig. 4, the binding strip 5 secures such sheet in place.

The batten strip may be longitudinally grooved if it is desired to stiffen the structure for heavy use; such construction is indicated in Fig. 7 wherein a strip having marginal flanges or beads 8 is folded on itself longitudinally throughout the transversely crowned web 9 to provide a rib 10 75 that is of sufficient depth to give the desired stiffness.

In addition to the complete shielding of the edges of the board by the metal binding, which is likewise ornamental in appearance, 80 the batten strips protect the dovetailed margins of their respective slots and give a good finish to the structure, the whole being fully protected from any splitting or checking, along the places where such action might 85 otherwise occur.

Obviously changes in details of construction may be made without departing from the spirit of the invention and I do not care to limit myself to any particular form or 90 arrangement of parts.

I claim as my invention:

1. A floor board for automobiles comprising pieces of sheet material provided with transverse slots having undercut margins 95 and with dovetail outer marginal portions, sheet metal strips having inturned marginal flanges that extend around and grip the dovetailed marginal portions of the assembled pieces and battens of sheet material provided with lateral flanges that engage under the under cut margins of the transverse slots and that overlie and inclose the outer edges thereof.

2. A floor board for automobiles comprising pieces of sheet material having trans-

versely disposed, registering slots with undercut margins and marginal portions that are dovetail in section, sheet metal battens in the slots, each having marginal longitudinal flanges and an initially crowned web flattened and expanded into the undercut marginal portions of the slots and the

flanges of the battens being adapted to bend around and envelop the outer edges of the slots, and marginal strips of sheet material flanged to embrace and interlock with the dovetail margins of the pieces. 10

LEONARD A. YOUNG.
